3-TIER PATIO TABLE

Alan Bedol, Shaker Heights, Ohio, assignor to The Marshallan Manufacturing Company, Cleveland, Ohio

Filed Mar. 13, 1970, Ser. No. 21,889

Term of patent 14 years

Int. Cl. D6—03

U.S. Cl. D33—14

Fig. 1

Fig. 2

FIG. 1 is a perspective view of a 3-tier patio table embodying my new design;

FIG. 2 is a vertical sectional view, taken along the line and in the direction of arrows 2—2 of FIG. 1.

I claim:

The ornamental design for 3-tier patio table, as shown.
